UNITED STATES PATENT OFFICE.

EARL J. REECE, OF DENVER, COLORADO.

HORSESHOE ATTACHMENT.

1,094,474.

Specification of Letters Patent.

Patented Apr. 28, 1914.

Application filed December 30, 1912. Serial No. 739,373.

To all whom it may concern:

Be it known that I, EARL J. REECE, a citizen of the United States, residing at Denver, in the county of Denver and State of Colorado, have invented certain new and useful Improvements in Horseshoe Attachments; and I do hereby declare the following to be a full, clear, and exact description of the invention, such as will enable others skilled in the art to which it appertains to make and use the same.

This invention relates to adjustable calks for horse shoes and has for an object to provide improved removable and replaceable structure carrying supplemental or additional calks applicable to an ordinary horse shoe and removable therefrom as conditions and circumstances may make desirable.

20 A further object of the invention is to provide in a structure of the class improved means for carrying the weight normally upon predetermined supporting points with means for bringing other engaging points 25 into engagement in case of slipping or lateral movement.

A further object of the invention is to provide improved means for attaching the structure to the shoe and hoof of a horse.

30 A further object of the invention is to provide improved means for positioning the calks laterally relative to the shoe.

With these and other objects in view the invention comprises certain novel constructions, combinations and arrangements of parts as will be hereinafter more fully described and claimed.

In the drawings: Figure 1 is a view of the structure in side elevation shown applied to a conventional horse shoe. Fig. 2 is an inverted plan view of the device attached to a shoe. Fig. 3 is a top plan view of a shoe with the calk members in position to be attached with the attaching member removed. Fig. 4 is a view in front elevation of the tension means at the front of the structure. Fig. 5 is a view in elevation of the connecting members, at the rear of the shoe. Fig. 6 is a top plan view of one of the calk members removed. Fig. 7 is a view of one of the calk members seen in end elevation. Fig. 8 is a sectional view through one of the calk members taken on line 8-8 of Fig. 6. Fig. 9 is a diagrammatic view showing the action of the calks under lateral slipping movement.

Like characters of reference designate corresponding parts throughout the several views.

The improved calk structure which forms the subject matter of this application is adapted to be used with a horse shoe of substantially the usual and ordinary form, the shoe being shown conventionally at 10 having the usual and ordinary toe calk 11 and heel calks 12. It is to be understood that the shoe 10 is to be nailed to the hoof of the horse in the usual manner and to be worn by the horse at all times. The additional or calk structure employed with the shoe 10 comprises a plurality of calk members shown at Fig. 6 each comprising a base 13 proportioned to engage against the under side of the shoe 10 and provided with an outer calk 14 and an inner shorter calk 15. Upon the base 13 a stud 16 is provided with a bracing member 17 pivotally mounted thereon and positioned to bear against the inner peripheral edge of the shoe as shown more particularly at Fig. 3. The bracing member 17 is triangular in shape as shown more especially at Figs. 3 and 6 with the several sides differently spaced from the stud 16 so that by rotating such bracing member upon the stud, space is provided to accommodate shoes of different sizes and constructed of different width material. The calk member is provided with a screw-eye 18 and four of such screw-eyes engage a central ring 19 to form a spider shaped arrangement of parts as shown at Figs. 2 and 3. The position of the calks relative to the ring 19 and consequently relative to the shoe 10 is predetermined by the adjustment of the screw 18 and the position of the bracing member 17. At their outer ends each of the calk members is provided with a headed stud 20 which extends beyond the lines of the shoe as indicated in Figs. 2 and 3 and is adapted to engage with the attaching structure.

The attaching structure comprises a pair of plates 21 at the front of the shoe having ears 22 engaged by a screw-bolt 23 and rear plates members 24 connected by means of strap members 25 which pass about the posterior part of the hoof and are connected by stud or bolt 26, holes 27 being provided to permit the varying of the length of such straps 25 and their connection. The rear plates 24 are also provided with holes 28 engaged by stud members 29 carried by the forward plates 21.

To adjust the device to the shoe of a horse the under structure is first adjusted to the proper shape and placed beneath the shoe with the upper attaching structure properly 5 adjusted by positioning the studs 26 and 29 in the holes 27 and 28 respectively and attaching the members to the stud 20 and then drawing the whole structure together over the front of the hoof by manipulating the 10 bolt 23. By this arrangement the entire device is clamped firmly upon the shoe to prevent rattling. While the calks 14 and the shorter calks 15 have been shown as positioned at the toe of the shoe it will be apparent 15 that calks 14' and 15' are similarly positioned relative to the heel of the shoe. The occasion for providing the calks of different lengths is that the calks 14 and 14' are positioned directly under the shoe structure 20 and under normal conditions the weight of the animal is carried directly upon such calks 14 and 14'. When, however, a slipping occurs there is a lateral motion upon the point of the calk 14 which serves to move 25 the base 13 relative to the shoe and to bring the calk 15 into engagement with the roadway. Under ordinary conditions of wear the calk 14 being subjected to the greater wear soon becomes dulled and is not, therefore, 30 capable of as great frictional resistance or of penetration as might be desired. The calk 15 or 15' being subjected normally to no wear retains its pointed condition so that when it is brought into engagement by the 35 slipping and lateral movement of the calk 14 or 14' it is in proper condition to resistingly engage the roadway and prevent further slipping.

By this arrangement the entire structure 40 may be removed and replaced readily, after once being adjusted, as occasioned by road conditions and when in place the normal wear will as above described be carried upon the calks 14 and 14' only while the calks 15 45 and 15' are retained as additional or auxiliary engaging means when slipping is occasioned.

It will be noted, especially from Figs. 8 and 9, that the axes of the calks 14 and 14' 50 extend vertically downward from the shoe while the axes of the calks 15 and 15' are inclined toward the center of the shoe. The

reason for this inclination will be obvious from an examination of Fig. 9 as the calks are tilted under a lateral movement in the 55 direction of the center of the shoe so that the calks 15 and 15' by reason of their inclination are better adapted to resist such lateral movement when brought into engagement with the pavement. 60

I claim:—

1. The combination with a horse shoe, of a calk structure detachably connected to the shoe and comprising a plurality of members 65 flexibly connected together centrally of the shoe, each of said members being provided with a calk disposed immediately beneath the shoe and an additional calk carried by each member shorter than the first mentioned calk. 70

2. The combination with a horse shoe, of a calk structure comprising a plurality of separate members flexibly connected together centrally of the shoe, each of said members being provided with a calk disposed immediately beneath the shoe, and an additional calk carried by each member 75 shorter than the first mentioned calk. 75

3. The combination with a horse shoe, of a calk structure comprising a plurality 80 of members flexibly connected together centrally of the shoe, means to adjust the radial position of the calk members relative to the central connecting member, a headed stud carried by each of the members and extending beyond the lines of the shoe and a securing structure comprising plates having means for engaging the studs, and other means for drawing such securing structure together. 90

4. As an article of manufacture, a calk structure proportioned to engage the under side of a horse shoe, said calk structure being composed of separate members flexibly united and each of said members comprising 95 an outer calk and an inner calk shorter than the outer calk. 95

In testimony whereof I affix my signature in presence of two witnesses.

EARL J. REECE.
